UNITED STATES PATENT OFFICE.

JOSEPH FAWELL, OF PITTSBURG, PENNSYLVANIA.

FEED-TABLE FOR ROLLING-MILLS.

No. 895,621.

Specification of Letters Patent. Patented Aug. 11, 1903.

Application filed June 27, 1907. Serial No. 331,177.

To all whom it may concern:

Be it known that I, JOSEPH FAWELL, residing at Pittsburg, in the county of Allegheny and State of Pennsylvania, a citizen of the United States, have invented or discovered certain new and useful Improvements in Feed-Tables for Rolling-Mills, of which improvements the following is a specification.

10 The invention described herein relates to certain improvements in feed tables for rolling mills and has for its object a construction in which the several parts or members are firmly secured together without the use of 15 nuts and bolts and permitting of the removal of the rollers without disturbing other portions of the table.

The invention is hereinafter more fully described and claimed.

20 In the accompanying drawings forming a part of this specification Figure 1 is a top plan view of a feed table embodying my improvement; Figs. 2 and 3 are elevations of opposite sides of the table, respectively; 25 Figs. 4 and 5 are sectional elevations on planes, respectively indicated by the lines IV—IV and V—V Fig. 1; Fig. 6 is a sectional plan view; Fig. 7 is a view similar to Fig. 4 illustrating a modification of my improvement; Fig. 8 is a sectional view on a plane indicated by the line VIII—VIII Fig. 7, and Fig. 9 is a detail view.

In the practice of my invention the sides 1 and 1^a of the table are formed by plates provided at suitable intervals with openings 2 and 3 for the reception of the journals 4 of the rolls 5. The plates 1 are also provided with longitudinal ribs 6 above the openings 2 and 3 and to the ribs are secured preferably by riveting, the side plates 7 forming guiding surfaces for articles moving along the table.

Brackets 9 are formed integral with the side plates, which are preferably formed by casting. These brackets are formed with heads or enlargements 10, which are recessed, as shown in Fig. 5, and in the inner ends of these recesses are formed seats for the reception of one half of the bearing blocks 11 for the horizontal shaft 12. The shaft is held in position by blocks 13 fitting in the recesses in the heads 10, and held in place by vertical keys 14 which being tapered and passing behind the blocks will 55 always hold them in proper position, com-

pensating for wear and will not be liable to accidental removal.

The openings 2 in one of the side plates as 1, is made only sufficiently larger than the journals of the rolls, to permit of the insertion of a bushing 15, which is provided with a flange 16 having a flattened portion adapted to rest on a ledge or shelf 17 whereby the bushing will be held from turning with the journal. The opening 3 in the other side 65 plate 1^a is made of a diameter of the body of the roll to permit of the latter being passed therethrough in placing the rolls in position and removing them therefrom. Annular blocks or bushes 18 are fitted in these openings 3, after the rolls have been passed through the same, said blocks having in their axial openings linings 19 forming the bearing surfaces for the journals of the rolls. The blocks or bushes 18 may be secured in 75 place in any suitable manner but they are preferably provided with wings 20 of such length that the ends of adjacent wings will be sufficiently close to permit both wings being engaged by the same rivet or bolt 21, 80 preferably the former. The brackets 9 are provided with arms 22 to which are hinged plates 23 covering the gear wheels 24 and 25 connecting the driving shaft 12 with the rolls. 85

It is the characteristic of my improvements that all the parts thereof are held in proper relative position without the use of nuts and bolts or other means liable to become loosened when using the table. Any one of the 90 rolls can be removed by cutting two rivets and removing the key 26 whereby the gear wheel 25 is secured to the roll journal. The longitudinal or driving shaft can be quickly removed when necessary by withdrawing the 95 keys or pins 14.

When rolling plates and sheets, it is necessary to feed them to the rolls with their longitudinal edges at an acute angle to the axes of the rolls, and to avoid the use of very wide 100 feed tables the side frames and rolls are so proportioned that the rolls will project above the side-frames, as shown in Fig. 7. When the rolls are made sufficiently large to project above the side-frames, and are so spaced that 105 the distance between the centers of adjacent rolls is approximately equal to the diameters of the rolls, the spaces or V-shaped gap between adjacent rolls is so great that slabs and short billets will tip in passing from one 110

roll to the next. In order to reduce this gap the rolls are formed with ribs 26 which are so located that the ribs on one roll will project between the ribs of adjacent rolls, as shown in Fig. 8.

In adapting my improvement to feed tables constructed as above described, the journals 28 of the rolls are made separable from the rolls, said journals being connected by a shaft 29. The journals are provided at their inner ends with seats 29 for the roll, which are held so as to turn with the shaft by any suitable means, as for example by keys 31, preferably formed integral with the seats, as shown in Figs. 7 and 8. In this construction, the journals and their connecting shaft are drawn out from the rolls through the opening in one of the side frames, the rolls being removed vertically after the journals are withdrawn. As only the journals are withdrawn through one of the frames, the bearing opening in said frame is not made much larger than the journal, as only the bearing bush or lining 19^a is employed, the annular blocks or filling bushes 18 being omitted. These bushes or linings are provided with wings similar to the wings 20, in the construction shown in Figs. 1 to 6, whereby the bushes may be held in position.

I claim herein as my invention:

1. A feed table for rolling mills having in combination rolls, side plates or frames provided with openings for the reception of the journals of the rolls, one of said openings being larger than the journals of the rolls to permit of the longitudinal removal of the journals through said opening and removable bushes arranged in said openings and forming bearings for the roll journals.

2. A feed table for rolling mills having in combination rolls, side plates or frames provided with openings therein for the reception

of the journals of the rolls, one of said openings being larger than the greatest diameter of the roll, and bushes arranged in said openings and forming bearings for the journals at that end of the rolls.

3. A feed table for rolling mills having in combination feed rolls, side plates or frames having bearings for the journals of the rolls, toothed wheels secured to the journals projecting beyond the side plates, a driving shaft provided with pinions intermeshing with the pinions on the rolls, brackets having slots for the reception of the driving shaft, the walls of said slots being parallel with a plane passing through the axis of the rolls and removable means for holding said shaft in bearings formed in said slots.

4. A feed table for rolling mills having side plates provided with openings for the reception of bearings for the roll journals, in combination with bearings for the journals of the rolls, one of the bearings for each roll having transverse dimensions greater than the diameter of the journals or portions of the roll between the journals and removable from the openings in the side plate to permit of the horizontal movement of the journals through one of the side plates to and from operative position.

5. A feed table for rolling mills having in combination rolls, side plates or frames having bearings for the journals of the rolls and provided with longitudinal ribs above said bearings and guide plates secured to said ribs.

In testimony whereof, I have hereunto set my hand.

JOSEPH FAWELL.
